Jay Cles Kroesen

UNITED STATES PATENT OFFICE

JAY CLEIS KROESEN, OF BELLEVILLE, NEW JERSEY

PICTURE SCREEN

Application filed April 7, 1928. Serial No. 268,089.

This invention relates to motion picture screens, and more particularly to a screen having means incorporated therewith for the emission of sound waves.

5 The invention provides for the propagation of sound waves from a motion picture screen and for the control of these waves whereby they may be emitted from the various portions of the screen in accordance with 10 the location of the images thereon, or may be emitted from the whole screen as a unit. This feature is particularly useful for talking motion pictures in order that the origin of the voice will simulate the location of the 15 actor or the point of the screen at which the action is taking place.

The invention further provides a screen having a magnetic material incorporated therein which may serve directly as an armature 20 of the electro-magnetic reproducing unit whereby the entire screen may be vibrated and operated as a source of sound waves. By dividing the screen or screen supporting mechanism into a plurality of 25 sections which may be operated independently, the waves can be reproduced from the necessary position to give a pleasing and natural effect.

The invention also consists in certain new 30 and original features of construction and combinations of parts hereinafter set forth and claimed.

Although the novel features which are believed to be characteristic of this invention 35 will be particularly pointed out in the claims appended hereto, the invention itself, as to its objects and advantages, the mode of its operation and the manner of its organization may be better understood by referring 40 to the following description taken in connection with the accompanying drawings forming a part thereof, in which

Fig. 1 is an elevation of a screen partly broken away showing the reproducers located in the rear thereof together with the switching mechanism for controlling the same;

Fig. 2 is a section taken on the line 2—2 of Fig. 1 showing the screen and sound reproducing unit;

Fig. 3 is a section view of a screen having magnetic material incorporated therein and forming the armature of a reproducing unit.

Fig. 4 is a sectional view of the screen for receiving a projected image and having a 55 stylus of an electromagnetic unit connected thereto;

Fig. 5 is a sectional view of a compound screen having a plurality of magnetic units associated therewith.

Like reference characters denote like parts in the several figures of the drawings.

In the following description and in the claims parts will be identified by specific names for convenience, but they are intended to be as generic in their application to similar parts as the art will permit.

Referring to the drawings more in detail and particularly to Fig. 1, a screen 10 is disclosed which may be mounted in any 70 suitable manner and is so formed as to be capable of receiving the image from the projection machine and at the same time passing sound waves therethrough from the reproducing units. Screen 10 may be divided into a plurality of sections, each of which is associated with a separate sound reproducing unit. The number of sections is shown in the drawing as 9, although any suitable number of divisions may be employed for producing the desired effect. 80 The screen may even be vibrated as a single unit if desired.

Reproducing unit 11 (Figs. 1 and 2) comprises a vibratory diaphragm 12 supported 85 by any suitable means as by framework 13 and an electro-magnetic reproducing unit 14 having a vibrating rod 15 secured thereto. Unit 14 may be mounted in any suitable manner as by brackets 16 supported 90 from framework 17, said framework being carried by a suitable backing plate 18 associated with framework 13. The particular form of reproducing unit, however, forms no part of the present invention, since 95 any desired source of sound waves may be employed.

Screen 10 may comprise the usual cloth screen which may be coated with suitable material for properly receiving projected 100

light. A plurality of leads 19 from the various units 11 may be brought out to a suitable switching means such as a switchboard 20 provided with a plurality of jacks 21. The 5 interconnection of the units may thus be controlled by suitable plugs 22 by means of which they may be selectively connected to a plurality of voice frequency lines, 27.

10 The switching means may be automatically operated or may be formed as a part of the screen and supporting mechanism.

15 The arrangement shown in Fig. 3 comprises a screen formed of a metallic wire section 23 formed of iron wire or other magnetic material and coated with a suitable material 24 such as cloth to produce the required surface for receiving projected pictures. Any desired coating may be applied to the screen, to impart the necessary optical properties thereto. Electro-magnetic unit 25 having pole pieces 26 may be located in operative relation with respect to magnetic material 23, and the same caused to 20 operate as an armature in a manner well known in the art. The screen surface may thus be vibrated directly and caused to project sound waves to the surrounding medium. Obviously a plurality of units 25 may be employed at different portions of 25 the screen to permit variation in the source of sound waves in the manner illustrated in Fig. 1.

30 In the arrangement shown in Fig. 4, a screen 35 is supported on a suitable framework 36 and is mechanically connected to a stylus 37 of an electro-magnetic reproducing unit 38. Stylus 37 may be connected to screen 35 in any desired manner and serves to impart vibrations to the screen surface 35 for the production and propagation of sound waves. The screen may be coated with any desired substance to impart the necessary properties thereto whereby motion pictures may be received upon its surface 40 simultaneously with the emission of sound waves. Unit 38 is preferably so associated with screen 35 that the latter is maintained in a substantially vertical plane, the amplitude of the sound vibrations ordinarily being 45 imperceptible to the audience.

50 In Fig. 5 a modification is shown comprising a screen formed of two sections. Outer section 30 is formed with a comparatively open mesh to permit sound waves to 55 readily pass therethrough. The backing screen 31 is formed of a usual material for receiving a projected image and is mechanically connected to the stylus 32 of an electro-magnetic unit 33. In order to impart 60 the necessary tension to screen 31, it may be stretched laterally, as shown in Fig. 5, into a slight conical formation. Vibrations of the electro-magnetic unit are imparted to the screen and cause the same to operate 65 as a loud speaker diaphragm. Coarse screen

30, however, is maintained in a single plane, and prevents distortion of the projected image which would otherwise occur. Provided the space between screen 30 or 31 is maintained comparatively small, the image which is received on screen 31 will appear to be formed on screen 30 and will be free from vibrations and from distortion due to the slight conical formation of screen 41.

70 Screen 31 is preferably formed with a 75 diffusing surface but not a reflecting surface. The diffusing surface possesses the properties of causing the image to appear on the outer screen whereas the reflecting surface would cause a double image to appear on the screen in places where screens 30 and 33 are not in exact parallelism.

80 In operating screens formed as above described, the lower group of reproducing units may be employed for the production 85 of music, whereas the upper groups may be variously used for speech in accordance with the instantaneous position of the actors, orchestra, etc. Any desired type of switching means may be employed for controlling the source of speech, one type of 90 which has been shown for purposes of illustration. It is understood, however, that this may be automatically accomplished in any desired manner such as from the projection machine itself or from the rear of the stage.

95 By employing a screen having magnetic material embedded therein, a plane surface is retained for the reception of pictures and mechanical interconnecting elements are 100 avoided. The arrangement shown in Fig. 2 is especially adapted to be installed in connection with the usual type of screen and may be used without replacing the screen itself. It is essential, however, that the screen be of sufficiently open mesh to 105 permit the sound waves to pass therethrough when necessary substantially unimpeded.

110 While certain novel features of the invention have been shown and described and are pointed out in the annexed claims, it will be understood that various omissions, substitutions and changes in the forms and details of the device illustrated and in its 115 operation may be made by those skilled in the art without departing from the spirit of the invention.

What is claimed is:

1. In combination with a picture screen, an electro-magnetic reproducing unit associated therewith, magnetic means incorporated in said screen and forming an armature for said reproducing unit whereby said screen may be vibrated and caused to propagate sound waves and may be simultaneously used for the display of pictures.

120 2. A picture screen comprising a mesh of magnetic material, a cloth backing incorporated therewith, said magnetic material being adapted to form the armature of an 125

electro-magnetic reproducing unit and to impart sound vibrations to said screen.

3. A motion picture screen comprising a cloth screen, a light receiving substance coated thereon, and a magnetic material incorporated therein.

4. In a motion picture screen, means associated with said screen for receiving a projected image and a plurality of variously located vibrating means for imparting sound frequency vibrations to said screen whereby the entire screen assembly is employed for the reception of an image and selected portions thereof are employed for the propagation of sound waves to cause said sound waves to appear to emanate from appropriate portions of the picture.

5. In a motion picture screen, means associated with said screen for receiving a projected image and a plurality of variously located vibrating means for imparting sound frequency vibrations to said screen whereby the entire screen is employed for the reception of an image and selected portions thereof are employed for the propagation of sound waves, to cause said sound waves to appear to emanate from appropriate portions of the picture, and switching means for selectively energizing said vibrating means.

6. A compound motion picture screen comprising a supporting mesh of magnetic material, a cloth covering thereover, said covering having a coating of a light receiving substance, said magnetic material serving as an armature and electro-magnetic means cooperating with said armature for vibrating said screen in accordance with sound waves whereby said screen may be simultaneously employed for the reception of an image and the propagation of sound waves.

7. A motion picture screen having a light receiving element and a magnetic element incorporated therein, means for mechanically sub-dividing the surface of said screen to provide a plurality of units which are capable of independent movement, said magnetic element serving as an armature and electro-magnetic means cooperating with said armature for independently imparting vibrations to each of said units whereby sound waves are propagated therefrom.

In testimony whereof I have hereunto set my hand.

JAY CLEIS KROESEN.
